UNITED STATES PATENT OFFICE.

WILLIAM GASTON JOBLING, OF CHATTANOOGA, TENNESSEE, ASSIGNOR
OF ONE-THIRD TO CHARLES E. HOOVER, OF RIDGEDALE, TENNESSEE.

REVERSIBLE PLOW.

SPECIFICATION forming part of Letters Patent No. 769,167, dated September 6, 1904.

Application filed June 25, 1903. Serial No. 163,074. (No model.)

To all whom it may concern:

Be it known that I, WILLIAM GASTON JOBLING, a citizen of the United States, residing at Chattanooga, in the county of Hamilton and 5 State of Tennessee, have invented new and useful Improvements in Reversible Plows, of which the following is a specification.

This invention relates particularly to reversing disk plows of that class in which the 10 plow is reversed by swinging the tongue to which the draft-animals are attached without turning the wheeled frame of the plow.

An object of the invention is to improve the means whereby the disk is reversed by the 15 swing of the tongue.

A further object of the invention is to produce improved means whereby the furrow-wheels will be equalized or adjusted angularly with respect to the line of draft by means of 20 the swing of the tongue.

A further object is to produce an improved land-wheel which will adjust itself to the angle of draft.

A further object is to improve the swiveling journal-boxes of the crank-axes of the furrow-wheels so that they may take the required draft adjustment without affecting their vertical adjustment.

A further object is to produce means for 30 automatically swinging the disk-scraper when the disk is reversed.

With these and other objects in view the invention is hereinafter described, and is illustrated in the accompanying drawings, in 35 which—

Figure 1 is a plan view of the plow. Fig. 2 is a side elevation thereof. Fig. 3 is a fragmentary end elevation showing one of the furrow-wheel supports. Fig. 4 is a detail in 40 section of the disk-holder and reversing attachment. Fig. 5 is a fragmentary side elevation of the land-side wheel, and Fig. 6 is a detail in plan view showing the wedge-shaped lug on the main frame which supports the reversing attachment.

Referring now specifically to the drawings, 1 indicates the main longitudinal beam, which may be made tubular or otherwise. This is joined to or cast with a semicircular plate 2,

projecting substantially horizontally on the 50 land side of the beam. The tongue 6 is pivoted at 6^a upon this plate and is adapted to swing around horizontally to reverse the plow. From the other or furrow side of the wheel a substantially horizontal wedge-shaped lug 3 55 projects. This is cast on the frame 1 and supports the reversing attachment, (indicated at 7.) This comprises a hollow wedge-shaped casting whose hollow 7^a is shaped to fit over the wedge 3, but is of greater width or angularity, so that the casting is free to swing horizontally until one of the sides thereof contacts with the side of the lug, the casting being pivoted upon the lug by a bolt 7^b at the point of the wedge. The width or angularity 60 of the wedge-shaped lug may be varied by removable pieces 3^a, bolted to the sides of the lug, as shown in Fig. 6, whereby the width of the furrow is regulated or wear taken up.

At the rear or base of the wedge-shaped 70 casting 7 is a pin 27, which projects vertically through a segmental slot 28 in the rear end of the tongue. When the tongue swings around, the pin strikes the end of the slot and turns the casting 7 on its pivot 7^b accordingly, 75 which has the effect of reversing the disk. The same effect is assisted or produced by crossed chains 40. These are connected at one end to opposite sides of the casting 7 and are then crossed and passed around rollers 40^a on the top of the beam and joined by rods 30 to the whiffletree 30^a. When the tongue is swung around, the respective chains will cause the casting to swing around to the other side and reverse the plow. Either the 80 slot-and-pin arrangement or the chains, or both, may be used to effect the reversal of the plow.

The casting 7 carries the bearing-box 7^c of the disk-holder 33, the disk attached thereto 90 being indicated at 10. The stem of the disk-holder has a rib 33^b around it, which fits in grooves in the bearing. The lower bearing is cast solid with the box 7^c; but the upper bearing 33^c is removable and adjustable by 95 means of the set-screw 34 behind it, so that the wear can be taken up.

The disk-scraper is indicated at 9 and is

carried at the outer end of a spring-arm 11, which works in notches at 8 upon the top of the casting 7. The scraper-arm 11 is bolted to the top of the casting 7 by a pivot-bolt, and 5 the inner end thereof projects into the path of studs 29 on the end of the tongue. When the tongue swings, one or the other of the studs strikes the scraper-arm and shifts the same into one or the other of the notches 8 to 10 throw the scraper across the face of the disk in the right position to work when the plow is reversed.

The furrow-wheels are indicated at 17 and 15 rotate upon crank-axes 15, which are carried in swiveling brackets 13 at the ends of the beam 1. The brackets swivel horizontally on hubs or bosses 14 at the ends of the beam, through which the pins 13^a of the brackets extend. Each bracket is also formed integrally with a segment-rack 16. The levers 18 to turn the axles to raise or lower the plow are fixed to the axles inside the brackets and have the usual spring-catches 19, which engage the segments to fix the plow at the desired height. A combined swiveling bracket and segment is thus produced, which is very effective for the purpose intended. The extended inner ends of the crank-axes 15 are connected by an equalizing-rod 23 for adjustment of the furrow-wheels to the line of draft. This rod carries adjustable collars 25, which are properly positioned to be engaged by the studs 29 when the tongue is shifted. The studs strike the collars and 30 throw the wheels and axles accordingly. The proper lead is secured by adjustment of the collars 25.

The land-side wheel 5 is carried on an axle 4, which is pivoted to the plate 2 conveniently 40 by the same bolt 6^a as the tongue. The axle is free to swing laterally between lugs 31 on the bottom of the plate 2, at the outer edge thereof, so that the wheel will take the proper direction of draft. The landside of the plow 45 may be raised or lowered by means of a bolt 32, which is vertically adjustable in a series of holes in the lugs.

In operation the plow may be run back and forth without turning the body and wheels 50 around by simply swinging the tongue on its pivot, which will have the effect of throwing over the casting or attachment 7, which carries the disk, thereby reversing the plow. As said before, this result may be effected by 55 either the chain or the slot-and-pin construction, or both. The swing of the tongue also throws the scraper across the disk to the proper position and changes the lead of the furrow-wheels accordingly. The land-side

wheel takes its proper position when the plow 60 is started.

What I claim as new, and desire to secure by Letters Patent, is—

1. In a reversible plow, the combination with the beam having a rigid wedge-shaped lug projecting therefrom, of a plow-support pivoted to the lug and abutting against one or the other of the sides thereof, a reversible tongue, and means actuated thereby to turn the support. 70

2. In a reversible plow, in combination, a beam having a rigid wedge-shaped lug, a plow-support pivoted at the point of the lug and having angular faces adapted to contact with the sides of the lug, and a reversible tongue 75 engaging the support and acting to reverse the same.

3. In a reversible plow, the combination with a wheeled beam, of a plow-support pivoted thereto, tongue-actuated means to reverse 80 the same, and an immovable abutment carried by the beam, having opposite faces against either of which the plow-support abuts.

4. In a reversible plow, the combination with a wheeled beam, and a reversible tongue 85 pivoted thereon and having a curved slot at the rear end, of a plow-support pivoted on the beam and having a pin projecting into the slot, to reverse the plow when the tongue is reversed. 90

5. In a reversible plow, the combination with a wheeled beam, and a reversible tongue pivoted thereon, of a reversible plow-support pivoted on the beam, and crossed chains connected to the tongue and the support, to reverse the latter when the tongue is reversed. 95

6. In a reversible plow, the combination with a beam and a reversible tongue pivoted thereto, of swiveling furrow-wheels connected by an equalizing-rod, adjustable collars on 100 the rod, and projections carried by the tongue, adapted to strike the collars and throw the wheels.

7. In a reversible plow, the combination with a wheeled beam having a wedge-shaped 105 abutment thereon, of a reversible plow-support having a hollow of greater angularity than the abutment and fitting thereover, a pivot-bolt connecting the abutment and the support, and a reversible tongue engaging the 110 support to reverse the same.

In testimony whereof I have signed my name to this specification in the presence of two subscribing witnesses.

WILLIAM GASTON JOBLING.
